ATTORNEY

UNITED STATES PATENT OFFICE.

ADOLF REIN, OF NEW YORK, N. Y.

LIFE-BELT.

1,284,773.

Specification of Letters Patent. Patented Nov. 12, 1918.

Application filed April 12, 1918. Serial No. 228,216.

To all whom it may concern:

Be it known that I, ADOLPH REIN, a subject of the Emperor of Austria-Hungary, residing in the city of New York, borough 5 of Manhattan, in the county and State of New York, have invented a certain new and useful Improvement in Life-Belts, of which the following is a specification.

The invention relates to belts or jackets 10 to be fastened about the body of the wearer and serve as a support in the water.

The object of the invention is to provide an easily applied belt of this character which shall be simple in construction, of 15 little weight, capable of being rolled or folded into small compass, and of great flotative capacity. A further object is to provide means for carrying a supply of water or liquid food sufficient to sustain 20 life for a limited period and easily drawn upon by the wearer of the belt while partially submerged.

The invention consists in certain novel features and details of construction and 25 arrangement by which the above objects are attained, to be hereinafter described and claimed.

The accompanying drawings form a part 30 of this specification and show an approved form of the invention.

Figure 1 is a perspective view of the improved belt. Fig. 2 is an elevation of one of the closed metallic cylinders serving as floats. Fig. 3 is a vertical section partly 35 in elevation, showing one of the floats adapted to contain water or liquid food. Fig. 4 is a horizontal section corresponding to Fig. 2 and taken on the line 4—4 in such figure with the stop-cock pipe removed.

Similar letters of reference indicate the 40 same parts in all the figures.

A is a belt or band of canvas or other suitable fabric adapted to apply about the body below the arms, and adjusted and held 45 to the body by the straps B B and buckles C C.

D D are hollow tightly closed cylindrical vessels of copper or other sheet metal, having 50 housings E E by which they are loosely secured to the belt, vertical thereto and in spaced relation to each other, adapted to serve as floats and support the wearer in the water.

The cylinders or floats are preferably located as shown in Fig. 1 in which one float 55 is at the center of the back, one on each

side of the hips, one between the center and side at the rear, and two in front near the ends of the belt, but the number and location may be varied. They may be secured 60 to the belt by any suitable means but preferably by the strips F F which extend parallel with the edges of the belt and are fastened thereto throughout their length except at the points where they pass through 65 the housings E E and form loops F¹ F² engaged with the latter.

The cylinders may be all similar but it is preferred to equip the cylinder D¹, at the front, with means for receiving and delivering water or condensed liquid food. It has a boss G at the top receiving a screw-threaded stop-cock H having a pipe H¹ extending downwardly therefrom in the interior of the cylinder nearly to the bottom, 75 and a nipple H² on the exterior adapted to receive an end of a rubber tube J.

The cylinder D¹ is filled by unscrewing the stop-cock H and removing it with its pipe H¹, and introducing the liquid through 80 the orifice thus provided. The stop-cock is then replaced and its plug turned to prevent the escape of the liquid.

By opening the stop-cock the contents may be drawn out by suction, through the mouth-piece J¹ on the free end of the tube J.

The bodies of the cylinders may be lengths of seamless drawn tubes, and the joints at the top and bottom are preferably double-seamed to insure against leakage; 90 the operation of double-seaming requires either the top or bottom or both to lie within the body of the cylinder and in these floats it is preferred to make the top flush and to elevate the bottom as in Fig. 3 so 95 that water will not be carried by the top, and the open space beneath the bottom may fill with air and serve to increase the buoyancy.

The loose connection of the floats to the 100 belt permits them to move laterally in accommodating themselves when the whole is rolled or folded for transportation or storage.

I claim:

1. A life-belt comprising a flexible band, fastening means therefor, strips independent of said fastening means and secured to said band, and vertically-disposed closed cylindrical floats loosely connected with said 110 strips for freedom of movement laterally to permit rolling of the belt.

2. A life-belt comprising a flexible band, fastening and adjusting means therefor, strips, independent of said fastening means, extending lengthwise of said band and secured thereto but unattached at points to form loops, and vertically-disposed closed floats having housings near their upper and

lower ends loosely receiving the said loops to permit freedom of lateral movement of the floats.

In testimony that I claim the invention above set forth I affix my signature. 10

ADOLF REIN.
